FILTERING OR DEWATERING PRESS.

1,366,307.

Specification of Letters Patent. Patented Jan. 18, 1921.

Application filed April 24, 1920. Serial No. 376,369.

To all whom it may concern:

Be it known that I, ABRAHAM TEN BOSCH, a subject of the Queen of the Netherlands, residing at The Hague, Netherlands, have 5 invented certain new and useful Improvements in Filtering or Dewatering Presses, of which the following is a specification.

This invention relates to filtering or dewatering presses.

- 10 If it is desired to dewater by means of a filter press peat, the colloidal state of which has been destroyed by a pre-treatment under pressure at an increased temperature, many and serious difficulties are experienced.
- 15 Early in the pressing operation the filtering material becomes choked up and in consequence the pressure in the cylinder rapidly increases. Under these conditions a pulpy mass accumulates behind the filtering material, which mass including the fibrous material contained therein is forced right through the strainer when the pressure in the cylinder rises to a certain limit; a considerable part of the fibers may thus escape 20 through the filtering material.
- 25 It has now been found that an excellent expression of the pretreated peat may be obtained in a press whose piston or cylinder cover or both is or are of such formation 30 that the outlet is formed by one or a plurality of narrow, for instance annular slots which are in communication with the cylinder through a space, the cross sectional area of which gradually decreases in a direction 35 from the interior of the cylinder to the said slot or slots. In a convenient embodiment of the invention the piston has the form of a hemisphere. The cylinder cover may have the same shape and, if desired, be movable 40 in a sense opposite that of the piston.

Another feature of my invention is the provision of a jacket inclosing the cylinder and allowing the material to be heated. It has been proved by experiment that the 45 press may also be used for expressing water from peat which has not been pretreated under pressure at increased temperature.

Still another feature of my present invention is the provision of narrow slots in 50 the piston or the cylinder cover or both, said slots during the pressing operation being in communication at one side with the afore-

said space of gradually decreasing cross-sectional area, and at the other side with the atmosphere. This construction allows of an 55 excellent dewatering of the central portion of the mass in the cylinder.

According to still another feature of the invention the cylinder space is in communication with the heating jacket through narrow slots the width of which preferably increases in the direction of the jacket. These additional slots in the walls of the cylinder insure a very rapid expression of moisture, and their increasing width in the direction 65 of the jacket reduces the resistance against the outflow of water and, consequently, the chance of their getting choked up. A very convenient construction is realized by composing the cylinder of a plurality of annular sections placed the one on the other and spaced apart by suitable distance pieces. If it is desired to change the width of the outlet slots of said cylinder all that is required 70 is replacing the said distance pieces by others of different thickness.

Other features of the invention will be more particularly pointed out in the claims.

The annexed drawing illustrates by way of example a longitudinal sectional view of 80 a press constructed in accordance with my present invention.

The illustrated press comprises a cylinder 1, a longitudinally slotted reciprocable piston 2 provided with a hemispherical head 85 and a central passage 3, and a hemispherical cylinder cover 4. Between the cylinder wall and the curved surface of the head of piston 2 is the above space of gradually decreasing cross-sectional area, ending in a 90 narrow annular slot 5.

The head of piston 2 is composed of a plurality of biconcave disks 6; its cap, however, is concavo-convex, and the base disk 95 plano-concavo. The edges of the said disks are kept equally spaced apart by means of distance pieces 7, and the slots thus formed have a width of say $\frac{1}{2}$ mm. each. With the exception of the cap, all disks are provided with a plurality of holes 8.

The cylinder 1 is built up of a number of annular sections 9 having lugs 10 by means of which they are firmly held together by bolts 11. The sections 9 have an approxi-

mately triangular cross-sectional shape, and their inner edges are kept spaced equally apart by distance pieces 12.

The cylinder cover 4 is not provided with 5 openings, but between the base of said body and the inner wall of the cylinder 1 is a narrow outlet slot 13.

The cylinder 1 is inclosed by a jacket 14 having a steam inlet nozzle 15 and a water 10 discharge nozzle 16.

The method of operation of the press is as follows:

After the cylinder 1 has been filled with raw peat, through the end in which the cylinder 4 is arranged, the piston 2 is forced inward until the pressure in the cylinder is about 75 lbs. Owing to this pressure the raw peat, which originally contained some 85-90% of water, releases part of its moisture which escapes mainly through the annular slot 5, but also through slots formed between the biconcave disks 6, and through the slots between the lower cylinder sections 9. Said moisture is allowed to flow off, in 25 some convenient manner. After this preliminary pressing operation the material adjacent to the piston 2 contains considerably less moisture than that in the remainder of cylinder 1.

Subsequently, the outlet 16 is closed, and 30 superheated steam of say 150° C. is admitted into the jacket 14, through nozzle 15. The said steam penetrates into the cylinder through the slots between the annular sections 9, and heats the peat so as to destroy 35 its colloidal state. During or after this steaming the piston 2 is forced farther into the cylinder to reduce the percentage of moisture in the peat to 30-35%, and the 40 water now expressed escapes mainly through the slot 13 and through the slots between the upper sections 9.

In a press as described the dewatering action in the piston head may be so intense, 45 that the briquet in the press strongly adheres to this head and cannot be removed without being damaged. In order to overcome this difficulty it is very convenient to couple the piston 2 with means such as a ring 50 17 with handles for imparting to it a rotary motion about its axis during or at the end of the pressing operation, whereby the briquet is released, for the briquet itself cannot follow this rotary motion seeing that 55 the frictional resistance of the cylinder walls, as a rule, exceeds that of the curved surface of the head.

In the press illustrated the curved surfaces of the disks 6 form together a spherical 60 surface owing to the area of the top face of a particular disk being slightly greater than that of the bottom face of the next higher disk. That is to say, said disks have along their circumference and at right angles to the 65 direction of motion of the piston an annular

surface which is in direct contact with the material to be treated, and in many instances the presence of said annular surfaces favorably affects the expression of the peat. If the area of the top face of any particular 70 disk were equal to that of the bottom face of the next higher disk, then owing to the presence of the distance pieces 7 the curved surfaces of the disks would not form a spherical surface, and the above annular 75 surfaces would not be present. This construction may be of value for the expression of water from certain other materials.

The briquet produced in the cylinder, may be removed from the press with a temperature of say 100° C. after which it may be crushed and, for instance, fed into a gas producer. However, the said briquet may also be pulverized and dried until its percentage of moisture is about 15%, after which the 85 pulverized material may again be pressed into briquets having a calorific value of about 5000 cal.

It is obvious that the filling of the cylinder, the pressing operation, the admission of 90 steam, etc., may be carried out automatically, but the manner in which this may be done does not form part of the present invention.

As already stated, the cylinder cover 4 95 might be made to act as a piston, when the piston 2 could be stationary, or the said members might be made to move simultaneously in opposite directions.

As to the cylinder cover and the piston 100 head, these need not necessarily be formed as hemispheres, as they may have the form of a cone, or of an ellipsoid, or any other convenient form, provided the space 105 enclosed between their surface and the cylinder wall has a gradually decreasing cross-sectional area. Furthermore, the said piston head or cylinder cover or both may be so formed that the narrow outlet slots corresponding to slots 5 and 13 are not circular but, for instance, run in a diametrical direction. In this case the space of gradually decreasing cross-sectional area may be 110 formed between two cylindrical surfaces.

It will further be understood that the 115 heating of the peat may be effected by means of hot air, or any other hot fluid, instead of superheated steam.

The expression "cylinder cover" in this specification should be interpreted to cover 120 the member serving during the pressing operation for closing the cylinder at the side opposite the piston.

Finally it is to be understood that the use 125 of my improved press is not limited to the expression of peat, and that said press may be advantageously used for the treatment of other materials.

What I claim is:

1. A press of the character described in- 130

cluding a cylinder, a piston in the cylinder consisting of a body longitudinally slotted on its outer surface for communication with the cylinder, and a head on the body shaped so as to leave an annular space between the head and the cylinder and the cross sectional area of the space decreasing in the direction from the end of the head to the slotted surface of the body of the piston, substantially as described.

2. A press as claimed in claim 1, wherein the piston is substantially in the form of a hemisphere, the base of which has an area which is slightly smaller than the cross sectional area of the cylinder, substantially as described.

3. A press as claimed in claim 1, wherein the cylinder is surrounded by a heating jacket.

4. A press as claimed in claim 1, wherein the piston is provided with a plurality of narrow slots which during the pressing operation are in communication at one side with the said space of decreasing cross-sectional area, and at the other side with the atmosphere.

5. A press as claimed in claim 4, wherein the piston and the cylinder are composed of a plurality of disks and distance pieces for spacing the disks with respect to each other.

6. A press as claimed in claim 4, wherein the piston is composed of a plurality of concavo-convex disks and distance pieces for spacing the disks.

7. A press as claimed in claim 4 wherein the piston is mounted in such manner that it may be rotated about the axis during or at the end of a pressing operation.

8. A press as claimed in claim 3, wherein the cylinder wall is provided with a plurality of narrow slots opening both in the cylinder and in the heating jacket.

9. A press as claimed in claim 8, wherein

the width of the slots in the cylinder wall 45 increases from the interior of the cylinder to the heating jacket.

10. A press as claimed in claim 1, wherein the cylinder is composed of a plurality of annular sections and distance pieces for 50 spacing said sections with respect to each other.

11. A press of the character described including a cylinder, a piston in the cylinder consisting of a body having a hollow head 55 formed with a plurality of narrow annular slots in communication with the cylinder, and each slot having a cross sectional area which decreases in the direction from the interior of the hollow head to the outer 60 surface thereof, substantially as described.

12. A press of the character described including a perforate cylinder having the respective ends open, a cylinder cover arranged at one end of the cylinder, a piston 65 arranged at the other end of the cylinder, the cover and the piston being provided with hemispherical shaped heads and mounted so that they may be moved relative to each other.

13. A press of the character described including a perforate cylinder having open ends, a cylinder cover arranged at one end of the cylinder, a piston arranged at the other end of the cylinder, a jacket surrounding the cylinder in spaced relation and supporting the cylinder and having openings in its ends for accommodating the cylinder cover and the piston.

14. A press of the character described including a perforate cylinder, a jacket surrounding the cylinder in spaced relation thereto, a cylinder cover for the cylinder and a perforate hollow headed piston operating in the cylinder for coacting with the 85 cylinder and the cylinder cover.

In testimony whereof I affix my signature.
ABRAHAM TEN BOSCH.
